WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,245,301.

Specification of Letters Patent.

Patented Nov. 6, 1917.

Application filed December 1, 1911, Serial No. 663,218. Renewed July 11, 1912. Serial No. 708,532.

To all whom it may concern:

Be it known that I, WALTER WRIGHT, a citizen of the United States, residing in New York city, in the county of New York and State of New York, have invented certain new and useful Improvements in Combined Type-Writing and Computing Machines, of which the following is a specification.

This invention relates to a new and improved key controlled correction mechanism to be used in connection with a combined typewriting and computing machine of the Underwood-Wright type, and is an improvement on my applications No. 543,603, filed 15 February 12, 1910 and No. 660,392, filed November 15, 1911.

In my above-mentioned application No. 660,392, I have provided means whereby the state of a computing head can be changed to just the opposite state without interfering with the direct state controlling mechanism of the computing head, by interposing between the source of power and the controlling mechanism for the individual computing heads a reversing mechanism which can be manipulated to change the direction of drive from the source of power to the gearing more nearly connected to the computing head, and having the individual state controlling mechanism interposed between it and the computing head. This, while useful with a single computing head, it is of a special advantage where a plurality of computing heads are used and it is desired to change the state of all the active heads to just the opposite state, whereby an error previously committed can be eliminated from the active computing heads, whether some had been adding, some neutral, some subtracting, or all adding, or all subtracting, by merely striking the same numeral key or keys which struck the erroneous numerals in the first place.

In the Underwood-Wright type of typewriting and computing machines, after the striking of a character, the typewriter carriage is fed a letter space to bring the next letter space of the work sheet opposite to the printing point. The movement of the traveling elements of the computing heads, which in this instance are shown to be the master wheels is controlled concomitantly with the movement of the carriage, so as to actuate the next computing or dial wheel at the next stroke of a numeral key. It is therefore

necessary in correcting an error to bring the carriage back to the letter space or digit column in which the error was committed, so as to bring the master wheels into cooperation with the proper computing wheels, and also so as to strike the numeral at the same point on the work sheet. As the operator generally notices the error immediately, the carriage and traveling elements may be brought back by a back spacer key. This key may be also used to change the state of the active computing heads.

An object therefore of this invention is to control concomitantly the return of the carriage and the traveling elements of the computing heads to a previous letter space and a change in state of all the active computing heads to just the opposite state, whereby an error committed in said letter space can be eliminated from all of the computing heads containing it.

To accomplish this object, the back spacer key is connected so as to not only shift the carriage back to one or more letter spaces, but also to temporarily shift the reversing mechanism between the source of power and the gearing for all the computing heads, to drive the active elements of the computing heads in just the opposite direction, whereby such of said computing heads as were subtracting at this particular letter space will add, and vice versa.

Other features and advantages will herein-after appear.

Referring to the drawings, Figure 1 is a side view in elevation with parts in section.

Fig. 2 is a diagrammatic perspective view showing the connection between one of the numeral keys and the valuating or escape- ment mechanism, whereby the extent of rotation is controlled according to the value of the particular numeral key struck.

Fig. 3 is a vertical section through one of the computing heads.

Fig. 4 is a skeleton perspective view showing the means whereby the back spacer key concomitantly back spaces the carriage and shifts the reversing mechanism located on the drive between the motor and the gearing connected to the computing heads.

Fig. 5 is a fragmentary side view in elevation, showing the reversing mechanism in its abnormal position.

Fig. 6 is a vertical detail section showing

the means for shifting one of the clutches of the reversing mechanism.

Fig. 7 is a detail of the tens carrying driving gear, and

5 Fig. 8 is a detail perspective view showing the back spacing mechanism in the act of shifting the carriage.

Referring more particularly to the separate parts of this invention as embodied in

10 the form shown in the drawings, 1 indicates letter keys and 2 numeral keys, which are secured to key levers 3, which operate through the intermediary of bell cranks 4, type bars 5, so as to swing the latter up
15 against the front side of a platen 6 carried by a carriage 7, which slides on one or more rails 8. The letter-feeding movement of the carriage 7 may be obtained in the usual manner step-by-step at each actuation of a key
20 by the release of an escapement mechanism, indicated generally by the numeral 9, which may be of the usual Underwood type, and is described more particularly hereinafter.

The computing mechanism may be controlled from the numeral keys 2 in the manner described in my application No. 543,603, wherein it was shown that each numeral key lever 3 was adapted to pull down on a link 10, so as to rock a bell crank 11, thereby
30 pulling on a link 12 to swing a lever 13 about its pivot 14. The swinging of each of the levers 13, of which there is one for each numeral key, plunges a jack 15 against a corresponding pin 16 provided in a master or
35 valuating wheel 17. The valuating wheel 17 is normally held from rotation by one of the projected pins 16 engaging an escapement wheel 18, which is secured to another escapement wheel 19 engaging one of a pair
40 of locking stops 20 on a rock shaft 21.

The rock shaft 21 is oscillated at each actuation of a numeral key, so as to release the escapement wheels 18 and 19, and thus permit a rotation of the master or valuating
45 wheel 17 a predetermined amount, depending upon the particular numeral key actuated, until the next projected pin 16 engages the escapement wheel 18. The rocking of the shaft 21 may be accomplished by a collar
50 150 being pushed back by each of the levers 13 at the actuation of a numeral key against the tension of a spring 151, so as to oscillate a lever 152 which is connected by a link 153 to an arm 154 on the shaft 21.

55 This mechanism, which may be termed the "escapement or valuating mechanism" for the computing mechanism, determines the extent of rotation of a shaft 22, to which the valuating wheel 17 is secured, and which
60 is provided with a gear 23 meshing with a corresponding gear 23' on a shaft 24. The shaft 24 is also provided with a bevel gear 25 meshing with bevel gears 26 and 27 secured respectively to shafts 28 and 29. The
65 shaft 29 is driven from a motor 30 through

the intermediary of a slip clutch not shown, and also through the intermediary of intermeshing bevel gears 31 and 32, the latter of which is secured to the shaft 29. The shafts 28 and 29 form a portion of the gearing connecting the motor 30 with the gearing for driving the rotatable parts of one or more computing heads 33 and 34, of which two are shown.

Each of the computing heads is preferably 75 of the type shown in my application No. 543,603 above-mentioned, and includes, as will be seen by reference to Fig. 3, a master wheel 35 splined on a shaft 36, so as to have a movement relative to a series of computing 80 wheels 37, whereby it will be capable of engaging with the internal gears 38 provided by the inwardly projecting teeth of these computing wheels, thus enabling the master wheel to successively actuate each of these 85 computing wheels. The relative movement of the master wheel and the computing wheels may be obtained in any suitable manner, as for example that described in my co-pending application No. 574,813, filed 90 August 1, 1910, wherein the master wheels are manipulated step-by-step at each new column by a lever 105 provided with an automatic catch 100, which is engaged and operated by a series of column stops 101 95 carried by a rack 102 on the carriage 7. These computing wheels are also provided with external teeth forming external gears 39 meshing with the gears 40 carrying the dial wheels 41, so that the numerals marked 100 on the dial wheels will be exhibited through an opening 42 in the casing of each computing head, thereby showing the particular computation run up by the numeral keys.

Each of the shafts 36 for the computing 105 heads 33 and 34 is provided with a bevel gear, indicated for the respective computing heads by the numerals 43 and 44. These bevel gears each mesh with a pair of bevel gears loosely mounted on a shaft 45 and 110 faced in opposite directions, so as to be capable of rotating the gears 43 and 44 in opposite directions, according to which member of the pair is rotated. To connect the pairs of bevel gears, which are indicated by 115 the numerals 46, 47, 48 and 49, in driving relation with the shaft 45, there are provided clutches 50 and 51 splined on the shaft 45, so as to be shiftable to cause the teeth provided on opposite ends thereof to 120 engage with corresponding teeth on the inwardly facing sides of each member of the pairs of bevel gears.

Each of the clutches is provided with a circular groove, so as to be engaged by pins 125 52 carried by shifting levers 53 and 54. The shifting levers 53 and 54 are pivoted respectively at 55 and 56 by means of pins, and are capable of occupying any one of three positions corresponding to the con- 130

nection of each of the gears of a pair in driving relation with the shaft 45, and also with a neutral position in which neither gear of the pair is in driving relation with the shaft 45. To secure the levers 53 and 54 in any position of adjustment, they are provided with a plurality of notches 57, preferably three in number, which are engaged by spring detents 58.

10 To connect the shaft 45 with the shaft 28 so that there will be an unbroken drive between the motor 30 and the master wheels 35, the shaft 45 has secured thereto a bevel gear 59, which meshes with a pair of oppositely facing bevel gears 60 and 61 loosely mounted on the shaft 28, but capable of being connected in driving relation therewith by a clutch 62, which is splined on the shaft 28, and has teeth on opposite ends thereof capable of engaging with corresponding teeth on the inwardly facing sides of the gears 60 and 61.

In the type of computing head shown herewith, it is essential to transfer a complete rotation of one of the lower computing wheels 37 to a partial rotation of the next highest computing wheel in the series. For this purpose, there is provided a tens carrying mechanism indicated in general by the numeral 63, which depends for its action, as described in my application No. 543,603, on the rotation and direction of rotation of a rubber roller 64. This rubber roller 64, in the case of computing heads 33 and 34, respectively, is connected to bevel gears 66 and 67 by a train of gearing, described in my application No. 543,603, and indicated in general by the numeral 65. The bevel gears 66 and 67 mesh with pairs 40 of bevel gears loosely mounted on a shaft 68, and indicated by the numerals 69, 70, 71 and 72. The pairs of bevel gears may be connected in driving relation with the shaft 68, so as to drive the bevel gears 66 45 and 67 in different directions by means of clutches 73 and 74, which are splined on the shaft 68, and capable of being slid, so that the teeth on opposite ends thereof will engage with corresponding teeth on the inwardly facing sides of each member of the pair of gears. The clutches 73 and 74 are provided with circular grooves engaged by pins 75 mounted on supplementary levers 76 and 77, which are pivoted respectively 55 on pins 78 and 79 secured respectively to the main shifting levers 53 and 54. These supplementary levers are each provided with a pair of fingers 80 and 81 projecting on opposite sides of the pivot pins 55 and 56, 60 so as to permit a limited motion of the supplementary levers relative to the main shifting levers. This limited motion or play may be taken up by springs 82 and 83, which are secured at one end to the supplementary levers and at the other end to the

pins 78 and 79. It will thus be seen that, by a simple movement of one of the levers 53 and 54, both of the clutches controlling the rotation and direction of rotation of both the master wheel and the tens carrying mechanism of a computing head can be simultaneously shifted, and thereby form a controlling mechanism for the state of the computing head, as to adding, subtracting or remaining neutral or inactive.

70 The shaft 68 may be also driven from the motor 30 by being provided with a bevel gear 84, which meshes with a bevel gear 85 secured on a counter shaft 86, which has a bevel gear 87 meshing with a bevel gear 88 8 on a shaft 89. The shaft 89 may be driven from the shaft 29, which as has been stated before is driven from the motor 30, by being provided with a gear 90 fixed thereon and meshing with both members of a pair 85 of gears 91 and 92 loosely mounted on the shaft 29, and facing in opposite directions, so as to be capable of driving the shaft 89 in opposite directions.

To connect the gears 91 and 92 in driving relation with the shaft 29, there is located between them a clutch 93 splined on the shaft 29 and shiftable from a position with its teeth on one end in engagement with corresponding teeth on the inner side 95 of the gear 91 to a position with the teeth on the opposite end thereof in engagement with corresponding teeth on the inner face of the gear 92.

It is desirable that both the clutch 62 100 and the clutch 93 be shifted simultaneously, so as to concomitantly control the direction of drive of the gearing for the master wheels and the gearing for the tens carrying mechanisms of all of the computing 105 heads. For this purpose, a shifter 94 is provided, which is shown in the form of a rod slidingly mounted in bearings 95, and having a pair of arms 96 and 97, which engage in circular grooves in the clutches 62 and 93. 110

In order to show the relation of the back spacing mechanism and the parts connected thereto, it will be well to describe at this point certain parts of the Underwood escapement mechanism 9, referred to in a 115 general manner above, whereby the carriage is fed step-by-step. For this purpose, each of the type bars is provided with a heel 106, which, at the actuation of each key, engages a universal bar 107 so that a pair of 120 pawls 108 are rocked back and forth to permit an escapement wheel 109 to advance one tooth. This escapement wheel 109 is connectible in one way to a pinion 110 which engages with a rack 111 pivotally mounted 125 on the carriage 7, so as to swing in and out of engagement with the pinion 110. The carriage 7 normally tends to move in a letter feeding direction under the pull of the spring indicated at 112. Back spacing of 130

the carriage 7 to bring the carriage back to a previous letter space for the purpose of correcting an error is accomplished in this instance by the depression of a key 113 secured to a key lever 114 secured to a rock shaft 115.

Secured to the shaft 115 there is provided an arm 115' which has extending upwardly therefrom a link bar 116, which is pivotally connected to an arm 117 extending to one side of and secured to an actuating pawl 118. The pawl 118 is also indirectly connected to the link bar 116 by having an arm 119 extending in the opposite direction from the arm 117 and connected to a pin 120 on the link bar 116 by means of a spring 121. This arrangement permits the bodily movement of the pawl 118 before rocking on its pivot 122, because of the fact that there is a substantially equal pull on each side of the pivot 122 of the pawl.

The pivot 122 of the pawl 118 is mounted on a rocker 123, which is pivoted at 124 so as to permit the rocker 123 to swing toward the rack 111 and bring the point of the pawl 118 into engagement with the teeth of the rack 111. The rocker 123 is provided with an overhang 125, which will overlie the rack 111 in its engaging position and prevent the disengagement of the rack from the pinion 110 while the pawl 118 is in engagement therewith. The rocker 123, however, is normally held out of engagement with the rack 111, and thus also the pawl 118 is normally held out of engagement with the rack 111 by means of a spring-pressed retriever 126 shown in the form of a pivotally mounted lever normally pressed in engagement with the side of the rack 111 by a spring 127. The forward movement of the rocker 123, and thus of the pawl 118 into engagement with the rack 111 will rock a locking pawl 128 into engagement with one of the teeth of the escapement wheel 109, so as to prevent the carriage 7 from moving forward under the pull of the spring while the back spacing key is depressed.

The pinion 110 is connected to the escapement wheel 109 by a pawl-and-ratchet mechanism, so that the carriage can move backwardly without rotating the escapement wheel 109 while the rack 111 is still in engagement with the pinion 110. This enables the striking of successive character keys in the same letter space while the back spacing key is depressed without feeding the carriage in a letter feeding direction.

Advantage is taken of the need to return to a previous letter space by means of the back spacing key, to actuate the shifter 94 against the tension of a spring 129, which normally holds the clutches 62 and 93 in connection with the gears 60 and 91. For this purpose the back spacing key 114 is provided with a depending link 130, which

has at its lower end a pin-and-slot connection 131 with one arm of a rocker 132 pivotally mounted intermediate its ends at 133. The other arm of this rocker 133 is provided with a finger 134 having an inclined cam surface 135 which is adapted to engage a pin 136 secured to an arm 137 on a rock shaft 138. The rock shaft 138 extends to a point where it is provided with a segment bevel gear 139 which meshes with a corresponding segment bevel gear 140 on a shaft 141. The shaft 141 is provided with an arm 142 having a slot 143 therein, whereby it engages with a pin 144 on the rod of the shifter 94. It will thus be seen that when the spacing key 113 is depressed, it will not only back space the carriage, but it will also manipulate, through the intermediary of the connecting mechanism, the shifter 94 against the tension of the spring 129, so as to manipulate the clutches 62 and 93 from engagement with the gears 60 and 91 into engagement with the gears 61 and 92.

In taking up the operation of the device, we will assume that an error has been made with the last key struck, and it is desired to eliminate the same from all of the computing heads which happened to be acting, whether they were adding or subtracting. To do this, it is merely necessary to depress the back spacing key 113, whereby the pawl 118 will be rocked forward until it comes in engagement with the teeth of the rack 111 when it will be swung against the tension of the spring 128 so as to move the carriage 7 back one letter or character space.

The movement of the rocker 123 which carries the pawl 118 will cause the concomitant movement of the locking pawl 128 into the path of one of the teeth of the escapement wheel 109, so that even if one of the numeral keys were struck while the back spacing key 113 is depressed, the carriage would not be fed forward in the usual manner. At the same time that the back spacing key returns the carriage one space, it actuates, through the intermediary of the connecting mechanism, the shifter 94, so as to bring the clutches 62 and 93 from engagement with the gears 60 and 91 into engagement with the gears 61 and 92, whereby these latter gears will be in driving relation with the shafts 28 and 29. This action will reverse the direction of drive of the gearing connected to both the master wheels 120 and the tens carrying mechanism of all of the computing heads, without disturbing their independent control, so that such of said computing heads as were adding, at the next actuation of a numeral key, will subtract, and vice versa. While the back spacing key is still depressed, the same numeral key which committed the error will be struck, so as to take out the exact amount of error which is put into each of the computing

heads, that is to say, if this number were previously added to a particular computing head, it will be subtracted, and if it were subtracted, will be added, so as to eliminate the error committed.

It will be seen that inasmuch as the locking pawl 128 still remains in engagement with one of the teeth of the escapement wheel, that so long as the back spacing key 10 is depressed, the carriage will not be fed forward. The back spacing key is now released, leaving the particular letter-space or digit column in which the error has been committed at the printing point. The erroneous numeral, 15 which has been struck twice in the same letter space, can then be erased from the sheet on the platen, and inasmuch as the carriage has been held in the same letter space, the proper key can then be struck, so that 20 the proper numeral will be imprinted on the work sheet, and properly computed in such of the computing heads as may be active at this particular instant.

Variations may be resorted to within the 25 scope of the invention, and portions of the improvements may be used without others.

Having thus described my invention, I claim:

1. The combination with a computing head having a series of computing wheels and a master wheel, said computing wheels and said master wheel having a movement relative to each other, whereby said master wheel may coöperate successively with each 35 of said computing wheels, of means for rotating said master wheel, and automatic means for concomitantly reversing the direction of rotation of said master wheel and changing the relative position of said computing wheels and said master wheel to a previous relation.

2. The combination with a computing head capable of being in a plurality of states as to adding, subtracting and remaining 45 neutral, of a carriage, and automatic means for concomitantly causing a backward movement of said carriage and changing the state of said computing head.

3. The combination with a computing head capable of being in a plurality of states as to adding, subtracting and remaining 50 neutral, of a carriage, and automatic means for concomitantly back spacing said carriage and changing the state of said computing head.

4. The combination with a computing head capable of existing under a plurality of states as to adding, subtracting and remaining neutral, of a typewriter carriage, 60 a key, means operated by said key for back spacing said carriage, and means operated by said key for changing the state of said computing head.

5. The combination with a computing head capable of existing under a plurality of

states as to adding, subtracting and remaining neutral, of a carriage, a key, means operated by said key for causing a movement of said carriage in a return direction, and means operated by said key for temporarily 70 changing the state of said computing head.

6. The combination with a computing head capable of existing under a plurality of states, of a carriage, and a key for concomitantly causing a backward movement 75 of said carriage and changing the state of said computing head.

7. The combination with a computing head including a rotatable master wheel and tens carrying mechanism, of gearing for 80 driving said master wheel having a shifting mechanism for controlling the drive thereof, gearing for driving said tens carrying mechanism having a shifting mechanism for controlling the drive thereof, 85 gearing controlling both sets of said gearing, including reversing mechanism to control the direction of rotation thereof, a carriage, and a key for controlling concomitantly the movement of said carriage and 90 said reversing mechanism.

8. The combination with a computing head including a rotatable master wheel and tens carrying mechanism, of gearing for 95 driving said master wheel having a shifting mechanism for controlling the drive thereof, gearing for driving said tens carrying mechanism having a shifting mechanism for controlling drive thereof, gearing controlling both sets of said gearing, including individual reversing mechanism for controlling the direction of said master wheel gearing and said tens carrying gearing, a carriage, and a key for causing concomitantly 100 a movement of said carriage and a shift of both of said individual reversing mechanisms.

9. The combination with a plurality of computing heads, each having a tens carrying mechanism, a reversing mechanism 110 therefor; a carriage, back spacing mechanism for said carriage, and means operated by said back spacing mechanism for shifting said reversing mechanism.

10. The combination with a plurality of computing heads, each having a master wheel and tens carrying mechanism, of gearing for driving said master wheels, 115 gearing for driving said tens carrying mechanism, each of said gearings including means for controlling the drive of said wheels and said tens carrying mechanisms, a carriage, back spacing mechanism for back spacing said carriage, and means operated by said back spacing mechanism for controlling both said gearings. 120

11. The combination with a computing head having a master wheel and tens carrying mechanism, of reversible gearing for driving said master wheel, reversible gear- 125

ing for driving said tens carrying mechanism, gearing for driving said first and second mentioned gearing, including a pair of clutches shiftable to change the direction 5 of rotation of said first and second-mentioned gearing, means for shifting said clutches simultaneously, a carriage, back spacing mechanism for back spacing said carriage, and means operated by said back 10 spacing mechanism for actuating said clutch shifting means.

12. The combination with a plurality of computing heads, each including a master wheel and a tens carrying mechanism, of 15 gearing for driving said master wheels in either direction, gearing for driving said tens carrying mechanism in either direction, gearing for driving said first and second mentioned gearing, including a pair of shift- 20 able clutches for determining the direction of drive of said first and second mentioned gearings, a shifter connected to both of said clutches for shifting said clutches simultaneously, a carriage, a back spacing mechanism 25 for shifting said carriage in a return direction, and connections between said back spacing mechanism and said shifter for manipulating said shifter.

13. The combination with a plurality of 30 computing heads, of individual controlling mechanism for determining the rotation and direction of rotation of each computing head, a supplementary controlling mechanism independent of said individual control- 35 ling mechanism for determining the rotation of said computing heads, a carriage, back spacing mechanism for back spacing said carriage, and connections between said back spacing mechanism and said second-mentioned controlling mechanism for actuating said second-mentioned controlling mechanism concomitantly with the back spacing of said carriage.

14. The combination with a plurality of 45 computing heads, of individual controlling mechanisms for determining whether said computing heads shall add, subtract or remain neutral, controlling mechanism independent of the actuation of said individual 50 controlling mechanisms, for enabling the opposite character of work of said computing heads to that determined by the individual controlling mechanisms when in an active position, a carriage, back spacing 55 mechanism for back spacing said carriage, and connections between said back spacing mechanism and said second-mentioned controlling mechanism for actuating said second-mentioned controlling mechanism con- 60 comitantly with the back spacing of said carriage.

15. The combination with a plurality of 65 computing heads capable of adding, subtracting and remaining neutral, of individual 70 controlling mechanisms for determining the state of said computing heads, a sup- 75 plementary controlling mechanism capable of changing such of said computing heads as are in their adding state to their subtracting state, and such of said computing heads as 70 are in their subtracting state to their adding state while said individual controlling mechanisms remain in the opposite state, a carriage, back spacing mechanism for back spacing said carriage, and connections be- 75 tween said back spacing mechanism and said second-mentioned controlling mecha- 80 nism for actuating said second-mentioned controlling mechanism concomitantly with the back spacing of said carriage.

16. The combination with a plurality of computing heads capable of adding, sub- 85 tracting and remaining neutral, of individual controlling mechanisms for determin- 90 ing the state of said computing heads, a supplementary controlling mechanism capable of changing such of said computing heads as are in their adding state to their subtracting state, and such of said computing heads as are in their subtracting state to their adding state, while leaving such of said computing heads as are in their neutral state free from interference, a carriage, back spacing mechanism for back spacing said carriage, and connections between said back 95 spacing mechanism and said second-mentioned controlling mechanism for actuating said second-mentioned controlling mechanism concomitantly with the back spacing of said carriage.

17. The combination with a carriage, of a back spacing mechanism for shifting said carriage in a return direction, a back spacing key lever for operating said back spacing mechanism, a computing head, means 105 for controlling the state of said computing head, an arm for operating said means, a shaft actuating said arm, a bevel gear on said shaft, a bevel gear meshing with said first-mentioned bevel gear, and connections 110 between said last-mentioned bevel gear and said back spacing key lever.

18. The combination with a carriage, of a back spacing mechanism for shifting said carriage in a return direction, a back spacing key lever for operating said back spacing mechanism, a computing head, means for controlling the state of said computing head, an arm for operating said means, a shaft actuating said arm, a bevel gear on 115 said shaft, a bevel gear meshing with said first-mentioned bevel gear, a shaft for rotating said last-mentioned bevel gear, an arm on said last-mentioned shaft, a rocker for actuating said last-mentioned arm, and 120 a link connecting said rocker with said back spacing key lever.

19. The combination with a carriage, of back spacing mechanism for said carriage, a key lever for actuating said back spacing 125 130

- mechanism, a computing head having a master wheel, tens carrying mechanism, gearing for driving both said master wheel and said tens carrying mechanism, individual clutches 5 for reversing said gearings, a shifter for manipulating said clutches, and connections between said shifter and said back spacing key lever, whereby said clutches may be shifted concomitantly with the actuation 10 of said back spacing mechanism.
20. The combination with a carriage, of back spacing mechanism for said carriage, a key for controlling said back spacing mechanism, one or more computing heads, state 15 controlling mechanism for determining the state of said computing heads, and means for temporarily changing the state of all of said computing heads which are active to just the opposite state while said back spacing key is depressed to back space said carriage.
21. The combination with a carriage, of a plurality of computing heads having traveling elements, a key, and connections between 25 said key and both said carriage and said computing heads, whereby an actuation of said key will concomitantly bring said carriage and said traveling elements back to a previous letter space and also change the 30 state of all of said computing heads which are active at the instant of actuation of said key.
22. The combination with a computing head having a series of computing wheels, 35 of a master wheel movable successively into cooperation with the computing wheels of said computing head, and an error key for concomitantly bringing said master wheel back into engagement with a previous computing wheel, and changing the direction of rotation of said master wheel to just the opposite direction to correct an error.
23. The combination with a computing head capable of existing in a plurality of 40 states as to adding, subtracting and remaining neutral, of a traveling carriage, and means for concomitantly moving said carriage backwardly and changing the state of said computing head at any point of the 45 travel of said carriage for a given adjustment of said head.
24. The combination with a computing head capable of existing in a plurality of states as to adding, subtracting and remaining 50 neutral, of a traveling carriage, and means connected to both said carriage and said computing head for concomitantly causing a backward movement of said carriage and a change in state of said computing 55 head.
25. The combination with a computing head having a series of computing wheels and a master wheel, said computing wheels and said master wheel having a movement 60 relative to each other whereby said master wheel may coöperate *seriatim* with each of said computing wheels, of means for rotating said master wheel, and means effective at any relative position of said master wheel and said computing wheels or when said master wheel is positioned relatively to said computing wheels, for concomitantly reversing the direction of rotation of said master wheel and bringing about a previous relative position of said computing wheels and said master wheel to correct an error.
26. The combination with a computing unit having a series of computing wheels, and a master wheel, said computing wheels and said master wheel having movement 70 relative to each other so as to enable said master wheel to register successively with each of said computing wheels, of driving means for rotating said master wheel, and a single means for concomitantly effecting a 75 relative backward movement between the master wheel and the computing wheels within the range of the computing unit, and changing the character of rotation of the master wheel.
27. The combination with a series of computing wheels, of a master wheel for driving said computing wheels *seriatim*, a reversible drive for said master wheel, and a single means for bringing about the registration of 80 said master wheel with a computing wheel with which it was previously in register so as to effect a correction and reversing the direction of rotation of said master wheel from that which it had when previously in register with such computing wheel.
28. The combination with a series of computing wheels, of a master wheel for driving said computing wheels *seriatim*, a reversible drive for said master wheel, a space key 85 connected to effect a relative backward movement between said master wheel and said computing wheels, and connections from said space key to said reversible drive enabling said space key to change the character of rotation of said master wheel.
29. The combination with a plurality of computing wheels, of actuating mechanism for driving said computing wheels, a series of numeral keys for controlling the extent 90 of movement of said actuating mechanism to correspond with the value of the numeral keys actuated, means for effecting denominational selections so that the successive actuations of numeral keys corresponding to successive denominations or digit columns will enable the operation by said actuating mechanism of the corresponding computing wheels, and correction mechanism acting automatically to both bring said actuating mechanism 95 in play with respect to a given computing wheel previously incorrectly rotated, and reverse the direction of actuation of said actuating mechanism to take out the number incorrectly run on such computing wheel.

30. The combination with a computing head, including a series of computing wheels and a master wheel for driving said computing wheels *seriatim*, of state-changing means 5 for varying the rotation of said master wheel, back-spacing mechanism for effecting a backward relative step movement between said computing wheels and said master wheel, and a single element having 10 a connection to said state-changing means and another connection to said back-spacing mechanism whereby it may operate both said state-changing means and said back-spacing mechanism at the same time.
- 15 31. The combination with a computing mechanism, including a series of computing wheels, of a carriage traveling to effect denominational selections with respect to said computing wheels, reversible mechanism in 20 dependent of the movement of said carriage for effecting a change of state in said computing mechanism at any letter-space interval in the travel of said carriage and at will, spacing means for causing the movement of said carriage, and a single member 25 for actuating both said spacing means and said reversible mechanism concomitantly.
32. The combination with a computing unit capable of existing under a plurality of 30 states as to adding, subtracting, and neutral, of a carriage traveling interzonally to determine different computing zones of said computing unit, and traveling intrazonally to determine denominational selections in zones for said 35 computing unit, and a single key for both changing the state of said computing unit and effecting an intrazonal movement of said carriage and thus a denominational selection of said computing unit.
- 40 33. The combination with a computing unit including a series of computing wheels and a master wheel, said computing wheels
- and said master wheel having a relative movement so that said master wheel may drive said computing wheels successively 45 when said master wheel is within the range of said computing wheels and thus within a computing zone, of intrazonally-acting means for concomitantly reversing the direction of rotation of said master wheel and 50 changing the relative position between said computing wheels and said master wheel, so that said master wheel will return from register with one computing wheel to register with the computing wheel with which it was 55 previously in register.
34. The combination with a computing unit capable of existing under a plurality of states as to adding, subtracting and neutral, of a traveling carriage controlling denominational selections of said computing unit, said carriage traveling also to determine computing zones and having step-by-step movements when in the range of a computing zone, and automatic means acting intrazonally in one 65 movement to concomitantly back-space said carriage and change the state of said computing unit.
35. The combination with a computing unit capable of existing under a plurality of 70 states as to adding, subtracting and neutral, of a carriage traveling interzonally to determine several computing zones for said computing unit, and traveling step by step intrazonally to determine denominational 75 selections in zones for said computing unit, and a common means for controlling both the state of said computing unit as to the character of computation and certain intra-zonal traveling movements of said carriage. 80
